METHOD AND APPARATUS FOR PREVENT-
ING OFFSET IN PRINTING

Theodore E. Knowlton, New York, N. Y.

Application August 30, 1930. Serial No. 478,840

20 Claims. (Cl. 101—422)

This invention relates to a method and apparatus for printing whereby both sides of a blank sheet may be printed with characters, marks, colors or symbols in clear, distinct outlines without any smearing or blurring resulting on the printed sheet. It pertains particularly to the impression or tympan cylinder or cylinders faced with a novel and improved printing blanket, or an off-set means associated with a printing apparatus.

The invention consists in the novel methods, combinations and arrangements hereinafter described for carrying out the above stated object and such other objects as will hereinafter appear.

This invention may be understood readily by reference to exemplifications of cylinder printing presses described in the following specification, in which same is used although it is not to be understood that the invention is limited to any particular printing apparatus. It may be employed with flat bed presses as well as with the cylinder type. In such exemplifications, a blank to be printed, for example paper, is fed through any conventional type of printing apparatus having one or both of the tympan cylinders provided with a printing blanket comprising a thin, smooth-surfaced, flexible structure, approximating in hardness the character of metal. Composition material of lesser stability than metal will not endure for any length of time the severe wear and tear to which it is subjected, and replacements are frequent. My invention aims to provide a printing blanket having the hardness and stability of metal, yet sufficiently flexible and elastic to yield under the compressing force of the impression cylinder. Illustration has been made only of that part of the printing apparatus which is utilized to carry the present invention into effect.

In the drawing:

Fig. 1 is a view in central vertical sectional elevation of that part of a printing apparatus embodying my invention;

Fig. 2 is a similar view of another modification;

Fig. 3 is a similar view of still another modification; and

Fig. 4 represents, on a larger scale, the peripheral structure of the second series of printing and tympan cylinders.

Referring to the drawing, 1 designates a blank sheet which is fed from reel A through a printing apparatus and then cut into sheets, wound upon reel B, or otherwise disposed of after it has been printed. The sheet is printed on both sides

by feeding same in contact with a series of printing rolls disposed to print first on one side and then on the reverse side of the blank. In the illustrated constructions, a series of printing cylinders are horizontally disposed with roll 2 arranged to print the sheet on the bottom side and the printing cylinder 3 arranged to print the sheet on the reverse side. Roll 4 is a conventional tympan cylinder cooperating with the printing cylinders 2 to support the blank while the printed matter is being imparted thereto, and numeral 6 typifies an inking device for the printing cylinders. While I have shown the printing cylinders to be horizontally disposed, it will be understood that this is merely one illustration. They may be vertically disposed or arranged in any other desired manner to print alternately on first one side and then on the other side of the blank without departing from the spirit of the invention.

Printing cylinder 3 of the second series of printing cylinders is similar to printing cylinder 2, and is likewise provided with an inking device represented at 7. However, after the blank has been printed on one side and is then printed on the reverse side before the ink has dried, care must be taken to avoid smearing or blurring on the printed side. It has been customary heretofore to run an offset sheet of ink-repellent material over the tympan cylinder 5 to avoid destruction of or injury to the printed side, but this has met with only partial success. Even though the offset be of a special grade of material, it will not prevent blurring of the outlines or avoid picking up the ink from the sheet while in contact with the blank. Because it does take on ink from the printed sheet, the offset sheet is unfit for continuous use without imminent danger of injury to the printed matter on the blank. When the offset sheet is constructed of rubberized fabric or the like, it soon cracks and peels.

I have discovered that a durable offset sheet may be constructed of a smooth, thin flexible material approximating in hardness the character of metal. This may be a single sheet inherently elastic and compressible as well as flexible, or it may be a composite structure, comprising a hard, flexible surfacing layer and a supporting layer of elastic and compressible material of different character.

A flexible metal is suitable for the smooth, thin surfacing layer and is typified by metal sheet 8 applied directly to the face of the tympan cylinder over a conventional printing blanket or any elastic sub-structure 9. It may be tightly

clamped over the face of the tympan cylinder in any well known manner (Fig. 1) or may be in the form of endless belt 12 (Fig. 2) circumvolved over tympan cylinder 5 and one or more idlers 13 and 14. In the modification of Fig. 3 the flexible metal sheet is in the form of a strip 15 adapted to be transferred from feed roll 16 over tympan roll 5 to a winding roll 17, after which it may be used repeatedly.

10 The invention is especially adapted for use in the printing of newspapers as well as for better quality work. The character of the metal sheet or the like is such that it may be readily cleaned without being softened or otherwise affected by 15 cleaning materials.

Obviously the present invention is not restricted to the particular embodiments herein shown and described, neither is it necessary that all features of the invention be used conjointly, since 20 they may be employed advantageously in various combinations and sub-combinations.

I claim:

1. A method of preventing offset in printing characterized by printing a blank sheet upon one 25 face, supporting the sheet on a smooth-surfaced, non-absorbent metal layer, and then printing the sheet on the reverse side.

2. A method of preventing offset in printing characterized by printing a blank sheet upon one 30 face, supporting the sheet on a relatively hard, smooth-surfaced, non-absorbent unitary flexible layer, and printing the sheet on the reverse side while same is supported on the relatively hard, flexible layer.

3. A method of concomitantly printing a blank sheet on opposite faces comprising feeding a blank sheet in contact with a printing element, traversing a relatively hard, smooth-surfaced, 40 non-absorbent unitary flexible layer in contact with the blank sheet, and immediately feeding the sheet in contact with a printing element while supported on said support to print the reverse side of the sheet.

4. A method of concomitantly printing a blank sheet on opposite faces comprising feeding one 45 face of a sheet in contact with a printing roll, traversing a smooth-surfaced, non-absorbent unitary flexible, relatively hard support with the sheet, and printing the reverse face of the sheet while on said relatively hard, flexible support.

5. A method of preventing offset in printing a blank sheet on opposite faces comprising printing one face of the sheet, supporting the sheet on the printed side over a relatively hard, smooth-surfaced, non-absorbent unitary surface, and simultaneously printing the reverse face.

6. The method of preventing offset in printing a blank sheet on opposite faces comprising first 60 printing one face of the sheet, traversing the sheet in contact with a smooth-surfaced, ink-repellent flexible metal layer, and simultaneously printing the reverse face.

7. The method of successively printing opposite faces of a continuously traversing sheet and supporting said sheet on a smooth-surfaced ink-repellent flexible metal layer to receive the subsequent print.

8. A method of preventing offset in printing characterized by printing a blank upon one face, supporting said blank on a platen with the 70 printed side in contact with a thin, smooth-surf-

faced, ink-repellent flexible metal layer, and printing the reverse side while in contact with the metal layer.

9. Printing apparatus comprising a series of printing rolls disposed to print on opposite faces of a sheet, tympan rolls cooperating with the printing rolls, and a relatively smooth-surfaced, ink-repellent hard, flexible layer homogeneous in character cooperating with the print roll which prints the reverse face of the sheet.

10. Printing apparatus comprising a series of printing elements disposed to print alternately on opposite faces of a sheet, supporting means cooperating with the printing elements, and a relatively smooth-surfaced, ink-repellent hard, flexible layer homogeneous in character associated with the subsequent supporting means to prevent dispersion of the ink on the initially printed face.

11. In a printing apparatus of the character described, means for successively printing on opposite sides of a continuously traversing sheet, and a relatively hard, smooth-surfaced non-absorbent layer of homogeneous character for supporting the sheet subsequent to the initial printing.

12. In a printing apparatus of the character described, a printing and tympan roll for printing one face of a sheet, a printing and tympan roll disposed to print the reverse side of the sheet, and a relatively hard, smooth-surfaced non-absorbent layer of homogeneous character traversing with the second tympan roll to contact with the printed face of the sheet.

13. In a printing apparatus of the character described, means for printing one face of a traversing sheet, means for printing the reverse face of the sheet, and a smooth-surfaced dry flexible metal faced tympan roll cooperating with the second printing means.

14. A printing apparatus of the character described comprising a printing device, a platen associated with the printing device, and means faced with a dry smooth-surfaced flexible metal layer cooperating with the platen to support a printed blank.

15. A printing apparatus comprising a printing device, a platen associated with the printing device, and a facing for the platen including a smooth-surfaced, ink-repellent flexible metal layer to support a printed blank.

16. A platen means for a printing apparatus having a smooth-surfaced ink-repellent layer of homogeneous character on which a printed sheet is adapted to be supported.

17. Printing apparatus comprising a series of printing rolls disposed to print on opposite faces of a blank, tympan rolls cooperating with the printing rolls, and a facing of smooth-surfaced ink-repellent flexible metal surrounding the tympan roll which supports the blank while being printed on the reverse side.

18. A platen means for a printing apparatus having a facing of smooth-surfaced, ink-repellent flexible metal on which a printed sheet is adapted to be supported.

19. A printing blanket consisting of a smooth-surfaced, ink-repellent flexible metal.

20. A printing blanket comprising superposed sheets, the exterior of which is a smooth-surfaced, ink-repellent flexible metal.

THEODORE E. KNOWLTON.
